INVENTOR

James Walker.

BY

A. Vinshup Wheatley
ATTORNEYS

UNITED STATES PATENT OFFICE.

JAMES WALKER, OF NETTLETON, PENNSYLVANIA.

COAL-MINING MACHINE.

Application filed February 4, 1921. Serial No. 442,501.

To all whom it may concern:

Be it known that I, JAMES WALKER, a citizen of the United States, residing at Nettleton, in the county of Cambria and State 5 of Pennsylvania, have invented certain new and useful Improvements in Coal-Mining Machines, of which the following is a specification.

This invention, which relates generally 10 to improved means for mining coal, is more particularly directed to improvements in that class of motor actuated mining machines in which the elements that constitute the machine provide for readily shifting the 15 entire mechanism, from one position to another, in the chamber in which the cuts are being made and by which the cutting elements are advanced into the coal vein, and, after making the primary incut into the 20 wall, the said elements, together with the entire machine structure, can be caused to move laterally, in either direction, to effect the cutting across and the removal of the face of the coal to a depth equal that of 25 the primary penetration of the cutting elements, at the start, the power means for actuating the cutting elements and effecting the lateral adjustment or shifting of the entire mechanism being effected wholly 30 by the power means obtained directly from the motor, which constitutes a part of and travels with the machine.

Generically, my invention embodies an 35 improved construction of coal mining machine of the character described, in which the operative parts are especially designed for transporting the complete machine across the floor or base of the cut and in such positions relatively to the wall to be 40 cut, whereby the cutting elements may be entered to begin the operation of effecting the primary or directly forward cut and, after making the said primary incut the full height of the chamber being mined, to 45 then provide for the lateral travelling of the cutting elements and the automatic travel of the machine, as the face of the wall, crosswise of the chamber, is being mined.

Among other objects, my invention seeks 50 to provide, in a coal mining mechanism of the character mentioned, an improved arrangement and construction of a base frame, a driving motor, cutting elements,

power transmission cooperative with the 55 motor and the cutting elements and including flexible connections, all so combined, whereby to provide a unit of mechanism, adapted, under its own power, for travelling across the mine floor and the place of beginning the cut and then readily adjusted 60 for causing the machine, with its cutting elements, to automatically move laterally across the wall being mined.

Another and essential object of my invention, is to provide, in a self-propelling coal 65 mining machine, an improved construction and arrangement of a vertically positioned rotary cutting head, which extends the full height of the chamber being cut, whose upper and lower ends are adapted for adjustment to suit the varying heights of the chambers and which operate to cut the top and bottom ends of the cuts, as the said cutting elements are caused to travel either directly into or laterally across the wall being 70 mined.

Furthermore, my invention comprehends, in a self-driven coal mining machine, an 75 improved construction of flexible power transmission, including pull cables for dragging the machine in straight lateral direction, when effecting the cutting operation or in a forward direction, when travelling into the cut for being placed at the primary cutting position along the face of the wall 80 to be reduced.

The said flexible transmission also includes a novel arrangement of a pair of winding drums with which the pull cables 85 cooperate and means for controlling the unwinding action of the drum for causing the said drum to wind in or pay out the pull cables in such manner that effects the desired lateral advancing of the entire machine and the cutting means that constitutes 90 a part thereof.

A still further object of my invention is to provide, in a coal mining machine of the general arrangement mentioned, an improved means for conveying the cuttings 100 made by the reducing elements, to the rear of the machine and in such manner that the said cuttings may be readily removed, mechanically or otherwise, to the dump.

With other more subordinate features 105 that will hereinafter be brought out, my in-

vention consists in a coal mining machine that embodies the peculiar features of construction, the combinations and arrangements of the parts fully stated in the following detailed description, as specifically set out in the appended claims and illustrated in the accompanying drawings, in which:

Figure 1 is a vertical longitudinal section of my coal mining machine, taken substantially on the line 1—1 on Figure 2, the motor and the cutting elements being shown in elevation.

Figure 2 is a plan view of my invention, parts being in horizontal section and illustrates the correlative connection of a flexible power transmission, one of the winding drums therefor being broken away for the purpose of illustration.

Figure 3 is a vertical cross section taken on the line 3—3 on Figure 2, looking in the direction of the arrow, parts being shown in end elevation.

Figure 4 is a detail face view, partly in section, of one of the winding drums and its cooperative driving pinion and brake device.

Figure 5 is a detail diagrammatic plan view illustrating one means of driving the coal conveyor devices.

Figures 6 and 7 are detail perspective views of two types of cutter members adapted for being used in connection with the rotary cutter head.

Figure 8 is a fragmentary vertical section taken through the cutter head and illustrating an extended adjustment thereof.

Figure 9 is a diagrammatic plan view illustrating the invention in varied positions.

In the drawings is illustrated a practical arrangement of a coal mining machine in which is embodied my invention, it being understood that the exact proportions and the cooperative connections may be modified or varied to suit the peculiar formation of the coal veins, thin or low, head room, &c.

My machine is especially designed for the compact assemblage of the operative parts and includes improved means that provide for readily shifting it from one position to another within the chambers of the mine, and to that end, the mechanism, that constitutes the machine proper, is supported upon a skid-like bottom 1 having upturned side and end flanges 2 within which the foot portions 30 of the machine base 3 fit and which engage the said side and end flanges, so that as power is applied to the machine proper, for moving it forward or backward or sidewise, the machine will freely drag the bottom support 1 to skid over the floor of the chamber, during the operation of adjusting the machine along the work or conveying it to and from the work across the mine floor.

4 designates the motor which may be of any approved type especially well adapted for mining machines and it is sustained on the main base 3, it being rigidly connected therewith.

Attached to the forward end of the motor casing are a pair of forwardly projecting bracket frames 5—5 whose outer ends constitute bearing supports 50—50 for the rotary cutting cylinder 6, that is vertically positioned in parallelism with the driving shaft 60 hereinafter further referred to.

In the present showing of my invention, the cutting head 6 comprises a cross-shaped body having the ends of its radial portions 52 annularly grooved for receiving the yoke-like bearing bands 50 that are fixedly secured, in any approved manner, to the outer ends of the bearing brackets 5, as is clearly shown in Figures 1, 2 and 5 of the drawings, from which, it will be noticed that the cutting head 6 includes a top section 64 on a stem 63 that is vertically adjustable within a central square socket 62 in the head 6 to provide for setting the top end of the cutter head to suit the high or low top wall of the chamber in which the machine is being used.

Drill bits 56—56 are attached to the outer edges of the radially projected body portions of the cylinder and to the top adjustable section 64, the said bits being of any suitable shape, for example as shown in Figures 6 and 7, and they are secured to the cutter body in any approved manner.

The propelling mechanism, which constitutes an essential part of my invention, is best shown in Figures 1, 2 and 3 of the drawings, by reference to which it will be seen the power shaft 7 from the engine carries a bevelled driving pinion 70 that meshes with a main driving gear 80 fixed upon the main driving shaft 60 that is vertically mounted at the rear of the motor, with its upper end journaled in a long bearing 81 which constitutes a part of a housing 82 that encloses the driving mechanism and protects the same against excessive coal dust deposit, the said housing, the formation of which is best seen in Figure 3, being supported upon and secured to the side portions 32 of the base frame 3.

The driven shaft 60 carries a vertical worm gear 83, which, at all times, meshes with an oppositely disposed pair of horizontal worm gears 85—85, each mounted on a separate shaft 86, that extend in parallelism, lengthwise of the machine, and are mounted in separate bearings 87—87 integral with the housing valves 82.

Each shaft 86, at the outer end thereof, has a worm gear 89 and each of the said gears 89 meshes with a worm gear 76 loosely mounted on shaft sections 77—77 disposed transversely across the rear end of the ma-

chine and journaled in bearings 73 that are formed on the side walls of the housing, as is clearly shown in Figures 2 and 3 of the drawings.

- 5 At the outer end, each driving shaft section 77 carries a pinion 75 and each of the said pinions meshes with an internal gear rim 90 of a winding drum 9, the said drums being oppositely disposed and located, one at 70 each side of the machine and loosely journaled on individual stub shafts 10-10 that project laterally from the upper or sub-frame members 35-35 of the main frame 3, as shown.
- 15 At the upper and lower ends, the shaft 60 carries chain drivers 12-12 provided with clutch faces 13-13. Endless power transmission chains 14-14 pass over the drivers 12-12 and over like drivers 15-15 attached 75 to the cutting head 6, by which, when power is applied to the chains 14-14, rotation is imparted to the cutter head for effecting the desired coal cutting operation.

Clutch members 16-16 are slidably 25 mounted on the upper and lower ends of the shaft 60 and are connected with suitable control lever devices 17, 18 and 19, whereby the chain transmission, for working the cutting head, may be readily thrown into and 30 out of connection with the power mechanism.

Referring now more particularly to Figures 3 and 4 of the drawings, it will be observed each winding drum 9 includes a hub 92 with which engage the well known type of brake band 20 cooperative with a brake lever 21, by which the drum can be retarded in rotation, it being understood the worm gears 76 are loosely mounted on their respective drum driving shafts 77, and at times connected with or disconnected from their respective shafts 77, by suitable clutch devices presently further explained, and at this point it should be mentioned the said 45 clutch devices provide for running both drums in unison, or running one drum and cutting out the other drum, at either side, according to the direction desired for advancing the machine either directly toward 50 the face of the wall to be worked, or laterally against the work in either direction.

In Figure 9 is shown, diagrammatically, a mine compartment and three positions of my improved mining machine and by now 55 referring to the said figure, in connection with the following description, the manner of operation of my machine will be readily understood.

The three positions of the machine are as 60 follows:

A. The machine is shown as being dragged, under its own power, to its cutting relation with the coal wall or face to be reduced.

65 B. The machine is here shown as having

started the cutting or wall reducing act and as being dragged, laterally, directly against and in parallelism with the face being reduced.

C. The machine is here shown as having 70 almost completed the reduction of the wall face to the predetermined depth, continuously across, after having travelled in the direction of the dotted arrows.

As has been heretofore described, the 75 drums 9-9 are, at times, to be rotated by the small pinions 75-75 at the outer end of each of the cross shaft sections 77. Wound around the drums are cables 93 and 94 with one of the ends of each cable made fast to its respective drum and the other end of the said cables adapted for being passed through guides 95 and 96 on the opposite sides of the forward end of the machine and then fastened to jack or other fixed posts 80 100 and 101 for the purpose presently explained.

Assuming now the machine has been 85 dragged into the mine chamber to the position A, Figure 9, in close proximity to the side wall *a* and with its longitudinal axis parallel with the said wall, the first operation is to now clutch into active condition the winding drum at the left of the machine and rigidly fasten the free end of the cable 93 to a jack or other rigid member straight 90 ahead of the machine. The parts being in the stated position and the motive power applied, it is obvious by reason of the connection of the cable with the drum and the rigid jack member, that by winding up the cable, the pull being now at the left side of the machine only, the applied power will tend to swing the machine forward and somewhat diagonally to the right, so that the cutter head will cut a starting pocket the full height of the wall and clear up 95 into the corner where the side wall *a* and the cross or face wall to be reduced, join.

100 After having made the initial cut at the corner, to the desired depth, the operation proceeds as follows:

First step.—By now passing the cable 93 mentioned over its guide sheave 95 at the left front side of the machine and securing it to a jack or post 100 and then again winding up the cable on the drum at that side, the machine will be pulled bodily laterally, in the direction of the cable connection 100 until the said machine attains its proper 115 parallel relation with the said wall *a*.

Second step.—The cable 94 that passes from the drum at the right side of the machine is now passed over the guide sheave 96 on the corresponding side of the machine and is made fast to a jack or other fixed connection 101, which positions the parts exactly as indicated by position B on the diagram Figure 9.

120 In order to obviate the necessity for a 130

stop while removing the entire face of the coal wall; or in other words, to provide for a continuous operation of reducing the coal face across the entire width of the wall being engaged without shifting the said position of the machine, the cable connection 100 may be moved clear over to the further side wall *b*, as indicated by position C.

Positioned as at B, the machine is now in readiness to start in lateral movement for effecting the removal of the desired layer of coal from the entire face of the wall being worked, and to a uniform depth.

After having completed the travel from B to the extreme opposite side of the chamber, after now making an initial direct bore into the opposite corner, by then clutching into operative condition the right winding drum and releasing the left drum from winding, so it will run free and pay out its cable, the entire machine, while retaining its relation at right angles to the wall face being cut, can be pulled bodily, laterally, the entire width of the coal face back to the other side for then repeating its reversed transfer travel.

It should be here mentioned that any suitable means for clutching the worms 76-76 with their respective shafts 77-77, as desired, may be employed, for example a pair of clutch sleeves 27-27, one for each shaft 77 may be provided and arranged as shown in Figures 2 and 3 of the drawings, which show each clutch sleeve 27 having a clutch face adapted for engaging coacting faces 78-78 on their respective adjacent worm gears 76-76.

79-79 designate levers for shifting the clutch sleeves as required.

By reason of the position of the guide pulleys 95-96 with relation to the weight of the machine and the resistance offered by the cutting head engaging the coal face, the pull on the winding cable 93 is such as will effect such bodily lateral movement of the machine over the mine floor, while the cable 94 on the opposite side of the machine is paying out and in order to compensate for any possible change in such balance of resistance, the brake 20 may be applied, as necessary, to the loosely running drum at the right side of the machine and thereby so regulate, by increasing and reducing the braking power, as to maintain the perfect balance of the resistance at the cutter head end.

It is understood that the left corner of the face of the wall to be cut is penetrated and cut away in a similar manner, as was the right hand corner, and by a mere reversal 60 of the operation stated.

In the practical application of my mining machine, suitable means is provided for gathering the cuttings made by the cutter head 6, as the latter is being constantly advanced to the work and for conveying the

said cuttings to the rear of the machine, from which they may be removed to the dump by manual or mechanical means.

In the drawings, for illustration, I have shown a gatherer 25 into which the cuttings are received and from which they are removed by a screw conveyer 26 that is mounted under the main base 3 and extends beyond the rear of the machine, as is indicated in Figures 1 and 2.

In practice, any suitable driving means may be employed for driving the coal carrying conveyor 26 but, in Figure 5 I have illustrated one means in which such drive may be practically effected. For this purpose, I provide the left hand worm shaft 86 with an extended portion 86^a adapted to pass through a bearing therefor in the corresponding casing half 82 and to be supported in a suitable bracket member 86^b fastened to the machine base. Between this shaft and the shaft of the conveyor a power transmission means 28 is provided whereby power is applied to the conveyor from the motor on the machine base and to provide for the cutting out of the driving relation of these parts as may be desired, I provide a shiftable clutch device 29, as shown.

It is to be understood that while the continuity of the cutting face presented to the coal wall by the rotary cutting head is broken at points, due to the positioning of the bearings 50, the transmission means co-operative therewith, and the adjustment of the adjustable section 64, this fact does not interfere with the cutting action, the spaces being insufficient to effect that fault, and the coal, being brittle, will be jarred from or fall naturally from such narrow areas as are not actually engaged by the cutting bits.

From the foregoing description taken in connection with the accompanying drawings, the complete construction, the manner of operation and the advantages of my coal mining machine will be readily apparent to those familiar with the art to which my said machine relates.

What I claim is:

1. A coal mining machine of the character described, comprising a base slidable over the mine floor, a power unit securely mounted upon said base to move therewith, a rotary cutting head supported upon and in advance of said power unit to rotate on a vertical axis, a pair of oppositely disposed winding drums loosely mounted upon horizontal axes, cables secured to said drums and to predetermined fixed points within the mine, transmission means for applying power from the power unit to the rotary cutting head and the drums, and means for retarding rotation of the drums as to cause bodily movement of the machine over the mine floor diagonally forward, straight forward or laterally.

2. A coal mining machine of the character described, comprising a base slideable over the mine floor, a power unit securely mounted upon said base to move therewith, 5 a rotary cutting head having a vertically adjustable portion and being supported upon and in advance of said power unit to rotate on a vertical axis, a pair of oppositely disposed winding drums loosely mounted upon 10 horizontal axes, cables secured to said drums and to predetermined fixed points within the mine, transmission means for applying power from the power unit to the rotary cutting head and the drums, 15 and means for retarding rotation of the drums as to cause bodily movement of the machine over the mine floor diagonally forward, straight forward or laterally, and means whereby the coal cut by the rotary 20 cutter head is gathered and conveyed rearwardly through the machine base.
3. A coal mining machine of the class described comprising the following elements in combination, a base slideable over the mine 25 floor, a power unit secure upon said base and slideable therewith, a vertically disposed rotary cutting head supported upon and in advance of said power unit, a driven shaft driven by said power unit, transmission 30 means for driving the rotary cutting head from said driven shaft, clutch devices for throwing in or out said power transmission at will, a pair of oppositely disposed winding drums each including an internal rim 35 gear portion and a hub portion, brake devices cooperative with said hub portions, power transmission means whereby each drum is driven independently of each other, clutch devices for causing said drums to 40 rotate in unison, singly or to be entirely inoperative, cables for cooperating with said drums, and guides for cooperating with said cables, substantially as shown and for the purposes described.
4. A coal mining machine of the class described comprising the following elements in combination, a base slideable over the mine floor, a power unit secure upon said base and slideable therewith, a vertically disposed rotary cutting head supported upon and in advance of said power unit, a driven shaft driven by said power unit, transmission 45
- means for driving the rotary cutting head from said driven shaft, clutch devices for throwing in or out said power transmission at will, a pair of oppositely disposed winding drums each including an internal rim gear portion and a hub portion, brake devices cooperative with said hub portions, power transmission means whereby each drum is driven independently of each other, clutch devices for causing said drums to rotate in unison, singly or to be entirely inoperative, cables for cooperating with said drums, and guides for cooperating with said cables, means for gathering the coal cut by the rotary cutting head, and means driven from said power unit whereby the gathered coal is conveyed rearwardly through the machine base.
5. A coal mining machine of the class described comprising the following elements in combination, a base slideable over the mine floor, a power unit secure upon said base and slideable therewith, a vertically disposed rotary cutting head supported upon and in advance of said power unit, a driven shaft driven by said power unit, transmission means for driving the rotary cutting head from said driven shaft, clutch devices for throwing in or out said power transmission at will, a pair of oppositely disposed winding drums each including an internal rim gear portion and a hub portion, brake devices cooperative with said hub portions, power transmission means whereby each drum is driven independently of each other, clutch devices for causing said drums to rotate in unison, singly or to be entirely inoperative, cables for cooperating with said drums, and guides for cooperating with said cables, means for gathering the coal cut by the rotary cutting head, and means driven from said power unit whereby the gathered coal is conveyed rearwardly through the machine base.

JAMES WALKER.
